(57) **CLAIM**

The ornamental design for a rehabilitation system, as shown and described.

DESCRIPTION

FIG. 1 is a perspective view of a rehabilitation system, taken from the front.

FIG. 2 is a perspective view of a rehabilitation system of FIG. 1, taken from the back.

FIG. 3 is a front view of the rehabilitation system of FIG. 1.

FIG. 4 is a back view of the rehabilitation system of FIG. 1.

FIG. 5 is a left-side view of the rehabilitation system of FIG. 1.

FIG. 6 is a right-side view of the rehabilitation system of FIG. 1.

FIG. 7 is a top view of the rehabilitation system of FIG. 1; and,

FIG. 8 is a bottom view of the rehabilitation system of FIG. 1.

The broken lines in the drawings illustrate portions of the rehabilitation system and form no part of the claimed design.
